UNITED STATES PATENT OFFICE.

AARON CARVER, OF LITTLE FALLS, NEW YORK.

IMPROVEMENT IN FORCE-PUMPS.

Specification forming part of Letters Patent No. 43,180, dated June 21, 1864.

To all whom it may concern:

Be it known that I, AARON CARVER, of Little Falls, in the county of Herkimer and State of New York, have invented a new and useful and Improved Single-Chamber Double-Acting Anti-Frost Force-Pump; and I do hereby declare that the same is described and represented in the following specification and drawings.

To enable others skilled in the art to make and use my improved pump, I will proceed to describe its construction and operation, referring to the drawings, in which the same letters indicate like parts in each of the figures.

Figure 1 is an elevation of my improved pump. Fig. 2 is a sectional elevation of the pump cut perpendicularly through the center; Figs. 3 and 4, plans of the upper and lower diaphragms; Fig. 4, a plan of the piston.

The nature of my invention and improvement in double-acting force-pumps consists in the construction and arrangement described and claimed in the following specification.

In the accompanying drawings, A is the cylinder, made of cast metal, open through its whole length and of a uniform size from end to end. The bottom plate, B, is fitted to the lower end of the cylinder and fastened by the bolts C C. This plate is made concave or hemispherical, with an opening, D, in the center for the water to enter below the piston, which opening D is closed by the ball-valve E. To prevent the ball E from being carried too far from the opening by the water, I fasten the diaphragm F (shown in plan in Fig. 4) in the lower end of the cylinder.

The diaphragm F is perforated to let the water pass freely through it, and provided with guide-pins G G, to hold the ball E right over the opening D. The top plate, H, is fastened to the cylinder by the bolts C C, which hold the bottom plate. The plate H has the pipe I extending up from it, to which a metal or wooden pipe may be connected to conduct the water pumped wherever desired. There are four holes, J J, in the top plate, H, for the water to enter above the piston, which holes are closed by the ball-valves K K, and to prevent the balls K from descending too far, I fasten the perforated diaphragm L (Fig. 3 is a plan) in the cylinder, by screws or otherwise, in the position shown in Fig. 2; and there

are some guide-pins, N N, in the top plate, H, which hold the balls K right under the holes J.

The piston P is shown in plan, Fig. 5, and in section in Fig. 2, and is fitted to the inside of the cylinder A, and consists of two horizontal plates, Q and R, connected by the hoop S, with the valve T between them. Both of the plates Q and R are perforated, as shown in Fig. 2, and when the piston is drawn up the valve T closes the holes in the plate R, and when the piston is forced down it closes the holes in the plate Q, so that the ring-valve T does double service. The plate Q is perforated in the center, and has the hollow piston-rod U fastened in it, which conducts the water pumped from the cylinder up into the pipe I, when it passes out of the rod through the opening V. The piston-rod may be connected to a crank, lever, or other device to work it. There is a hole in the pipe I at W, and a hole in the piston-rod right opposite to it, to let the water out of the pipes before it freezes. There is a recess, X, on the inside of the pipe I, so that if the piston-rod is turned the water will run through the hole in the rod and around in the recess to the hole W, so as not to freeze up in the pipes above the pump.

The operation of the above-described pump is as follows, viz: When the piston is drawn up, the valve T closes the holes in the plate R, and the water is drawn in by the valve E and fills the cylinder below the piston. When the piston is forced down, the valve E closes, and the valve T closes the holes in the plate Q, so that the water below the piston is forced through the hole in the valve T, up through the piston-rod. When the piston was forced down, it drew the water in by the valves K K and filled the cylinder above the piston, so that when the piston is raised the valves K close, and the ring-valve T closes the holes in the plate R, and the water above the piston passes through the plate Q and up through the piston-rod.

I claim—

1. The cylinder A, provided with ports and valves at both ends, substantially as described, in combination with the peculiarly constructed piston P and hollow piston-rod.

2. The combination and arrangement of the recess X in the pipe I with the hole W and the hole in the piston-rod, the hole in the pis-

ton-rod being opposite the recess X when the piston is down.

3. In combination with the valve E and diaphragm F, the guides G, which hold the valve over the opening when it is raised.

4. In combination with the cylinder, the top plate, H, provided with holes for the water to enter above the piston and with seats for the ball-valves, substantially as described.

5. In combination with the perforated top plate, H, and cylinder A, the perforated diaphragm L, which holds the ball-valves near their seats.

6. In combination with the ball-valves K and top plate, H, the guide-pins N on the top plate, which hold the valves under their seats.

7. The hole W in the pipe I, in combination with the recess X in the pipe and the hole in the piston-rod, to let the water out of the pipes before it freezes.

8. In combination with the ring-valve and piston, the hollow piston-rod.

AARON CARVER.
